UNITED STATES PATENT OFFICE.

ROY E. SAGLE, OF ROSEVILLE, OHIO.

SPOT-LIGHT.

1,355,783.

Specification of Letters Patent. Patented Oct. 12, 1920.

Application filed December 27, 1919. Serial No. 347,879.

To all whom it may concern:

Be it known that I, ROY E. SAGLE, a citizen of the United States, residing at Roseville, in the county of Muskingum and State of Ohio, have invented certain new and useful Improvements in Spot-Lights, of which the following is a specification.

This invention relates to an improvement in spot lights more particularly for use on 10 motor vehicles, and constructed with a view to providing an efficient means for controlling the beam direction, and to providing a mounting for the spot light so that complete regulation and control thereof may be had 15 without the necessity of reaching beyond the side of the car for such purpose.

The improved spot light is supported in a bracket made up of independent tubular sections, cables arranged to pass through 20 such tubular sections being provided for adjusting the light, such tubular sections also housing the electric conductor. The adjacent ends of aligned sections through which the cables pass, have threaded connection in 25 a bearing sleeve, whereby the sections may be adjusted as a proper tension on the cables may require. The bearing sleeve is rotatively mounted in a bracket secured to the car, so that the operating end of the structure may project within the car, to thereby permit full control by the driver without the necessity of reaching beyond the protected area of the car for such purpose.

In the drawing:

35 Figure 1 is a view in vertical section illustrative of the invention.

Fig. 2 is a plan of the same.

The present invention is directed more particularly to what may be termed the arm member of the spot light, and which, as shown is made up of a hollow yoke 1 and tubular sections 2 and 3 projecting therefrom. The section 2 is secured to the yoke, and said sections 2 and 3 are arranged in alignment and their proximate ends are threaded at 4 into a bearing sleeve 5. The lamp casing or bowl 6 is mounted for the usual swinging movement between the ends of the yoke, and aside from the following particulars may be of any desired form or structure. The bowl 6 is held in the yoke at diametrically opposite points, one such connection comprising a tubular extension 7 on the bowl, to rotatively engage a correspondingly shaped lateral projection 9 of one yoke end. The opposite mounting of

the bowl involves a cylindrical enlargement 10 of the yoke end, opening toward the bowl, in which enlargement is arranged a pulley member 11 fixed to the bowl by a bolt 12, 60 which has a rotative mounting in the outer wall of the enlargement and is held within the bowl by a nut 13. The bowl is thus rotatively mounted within the yoke, and is provided with a relatively fixed pulley completely housed within the hollow yoke. 65

The free or inner end of the section 3 is circumferentially enlarged to provide a casing 14 the side opening of which is closed by a removable plate 15. A shaft 16 is 70 mounted transverse the casing 14, and provided within the casing with a pulley 17, and beyond the casing with a hand wheel 18.

Operating cables 19 and 20 connect the respective pulleys 11 and 17 and between the 75 pulleys are housed in the tubular formation of the parts. These cables are mounted so as to bear approximately centrally of the respective pulley, and are oppositely connected to said pulleys. For example cable 80 19 passes centrally over pulley 17, with its end deflected from the center line of the pulley and connected to one side of such line on the lower side of said pulley. The opposite end of cable 19 passes beneath 85 pulley 11 in the central line thereof with its end deflected from the center line and secured on the upper side of the pulley. Cable 20 is similarly though reversely connected to the respective pulleys, the operating 90 parts of the cable 20 passing over the center line of the pulley.

With this arrangement it is apparent that by manipulation of the hand wheel 18 the 95 spot light may be moved as desired in its pivotal mounting in the yoke, each pulley taking up the slack of the nonactive cable. Furthermore by the obvious rotation of the bearing sleeve 5 the sections 2 and 3 may be spaced as required to properly tension the 100 cables and thereby maintain the adjusting means efficient, notwithstanding the stretch of the cables following continuous use.

The energizing conductor 21 for the lamp socket passes through the mounting 7, 105 through the hollow yoke and through a protected tube 22 secured to and resting within the section 3 and extending into but not secured to the section 2. The conductor passes through a nipple 23 to the battery, 110 and from the battery a conductor 24 extends through the nipple 23 into the tube 22 and

to an insulated contact point 25 in the wall of the housing 14. A switch plate 26 is adapted to be engaged with the contact point 25 at will, to thereby close the light circuit, the other side of the circuit being grounded through the structure.

The spot light as a whole is mounted in a bracket 27 to be removably secured to the automobile as the wind-shield post, or other appropriate part. The receiving end of this bracket comprises separable sections 28, 29 adapted to be clamped about the bearing sleeve 5 with sufficient friction to support the structure without interfering with rotative movement of such sleeve and spot light structure. This mounting provides for the adjustment of a spot light in the direction at right angles to that permitted by the yoke mounting, thus providing the necessary universal adjustment.

The receiving end of the bracket end 27 is mounted at right angles to the length of the car, and such bracket may if desired be fixed in this position. The free end of the spot light structure is thus arranged wholly within the car, and all adjustments of the like, as well as the energization and de-energization thereof may be carried out by the driver without the necessity of reaching beyond the car. This is a desirable feature particularly in closed cars, or where there is a necessity for the use of protected curtains in open cars. By this mounting the driver has perfect control of the spot light without

the necessity of opening a window or loosening the curtains.

What I claim is:

1. A spot light including a hollow yoke having a threaded extension, a lamp bowl pivotally supported between the ends of the yoke, a tubular section threaded at one end and formed at its opposite end with a circumferentially enlarged casing, a threaded bearing sleeve flanged at opposite ends, the threaded extension of the yoke and the threaded end of the tubular section engaging the threaded nut, a bearing supporting the nut between the flanges, a pulley mounted in the housing, a pulley mounted to rotate with the lamp bowl, and a cable passing around the pulleys to turn the lamp bowl.

2. A spot light having a hollow yoke provided with a threaded extension, a lamp bowl pivotally mounted in the yoke, a tubular section in alignment with the extension and threaded at one end, a tube secured within the tubular section and extending into the tubular extension, a threaded bearing nut engaging the threaded ends of the extension and the tubular member, the opposite ends of the bearing nut having flanges, a support engaging said nut between the flanges, and means carried by the tubular member and extending through same and the yoke to the lamp for turning the latter.

In testimony whereof I affix my signature.
ROY E. SAGLE.
